UNITED STATES PATENT OFFICE.

PIETRO JACOVINI, OF PHILADELPHIA, PENNSYLVANIA.

DESIGN FOR A NEWSPAPER AND PARCEL HOLDER.

59,492.

Specification for Design.

Patented Oct. 25, 1921.

Application filed February 4, 1921. Serial No. 442,551. Term of patent 7 years.

To all whom it may concern:

Be it known that I, PIETRO JACOVINI, a citizen of the United States, residing at Philadelphia, in the county of Philadelphia, State of Pennsylvania, have invented a new, original, and ornamental Design for a Newspaper and Parcel Holder, of which the following is a specification, reference being had to the accompanying drawings, forming part thereof.

I claim:—

The ornamental design for a newspaper and parcel holder, as shown.

PIETRO JACOVINI.
